COMBINATION CARBIDE AND WATER
CONTAINER

Gould C. McIntyre, Hopewell, Va.

Application March 16, 1934, Serial No. 715,967

1 Claim. (Cl. 220—5)

This invention appertains to new and useful improvements in miner's equipment, and more particularly to a novel container whereby carbide and water can be conveniently carried about the person of the miner so that he will have a supply of these items always at hand for his convenience.

An important object of the present invention is to provide a combination miner's device of the character stated which can be readily carried on a waist belt without discomfort.

Another important object of the invention is to provide a combined carbide and water container for miners wherein the container is in sections and separately connected so that they can be used independently.

These and various other important objects and advantages of the invention will become apparent to the reader of the following specification.

In the drawing:

20 Figure 1 represents a side elevational view of the container with a portion broken away to disclose the manner in which the sections are fastened together.

25 Figure 2 represents a sectional view taken substantially on line 2—2 of Figure 1.

Figure 3 represents a top plan view of the container.

Referring to the drawing wherein like numerals designate like parts, it can be seen that the container is of substantially circular shape and that the sections are substantially semi-circular in shape, with their straight vertical walls in opposed relation. The section A is provided at its inside wall 5 with a lip 6 at its upper end and 35 along its vertical edge portions with a grooveway 7. The container section A is intended for carbide and has a relatively large filler neck 8

equipped with a cap 9 in comparison to the smaller filler neck 10 and cap 11 for the water containing section B. The section B has an in-turned flange or tongue 12 at each vertical edge portion and obviously, by starting these tongues 60 at the lower ends of the slots or grooveways 7, the section B can be slid onto the section A so that they mesh to form a complete circular container, as shown in Figure 1. A swingable latch 13 is provided on the lower portion of the section 65 A and is preferably of spring material so that the same can be swung to the position shown in full lines in Figure 1 to tensionally engage the bottom of the section B and retain the same properly connected with the section A. Each of the sections A—B is provided with a belt engaging clip 14 at its back side so that the container can be readily carried on the belt.

While the foregoing specification sets forth the invention in specific terms, it is to be understood 75 that numerous changes in the shape, size and materials may be resorted to without departing from the spirit and scope of the invention as claimed hereinafter.

Having described the invention, what is claimed 80 as new is:—

A container of the character described comprising a pair of semi-circular shaped containers provided with tongue and groove connections on their opposed sides, one of said sections being 85 provided with a lip at one end to limit the movement of the other section on the same, one of the said sections being provided with a latch which can be swung to engage the other container section to retain the same in connected position with 90 its complementary section.

GOULD C. McINTYRE.
